UNITED STATES PATENT OFFICE.

MICHAEL DESPOT, OF DAYTON, OHIO.

COLLAPSIBLE HAND-BAG.

1,166,336.

Specification of Letters Patent. Patented Dec. 28, 1915.

Application filed July 17, 1915. Serial No. 40,505.

To all whom it may concern:

Be it known that I, MICHAEL DESPOT, a subject of the King of Hungary, residing at Dayton, in the county of Montgomery and State of Ohio, have invented certain new and useful Improvements in Collapsible Hand-Bags, of which the following is a specification.

This invention relates to new and useful improvements in collapsible hand bag.

The primary object of the present invention is the provision of a hand bag of light weight which is cheap and inexpensive to manufacture and which may be readily collapsed or folded compactly when not in use as may be found desirable.

A further object of the device is the provision of a frame-work for a collapsible bag covering and adapted for closing compactly when desired and when expanded positions the covering firmly stretched in its hand bag formation.

A still further object is to provide a foldable hand bag frame with a flexible covering and with non-flexible lid members for closing the mouth of the bag which is contracted relatively of the point of greatest cross sectional area of the device when operatively positioned, oppositely arranged bail carrying handles being also provided.

With these general objects in view and others that will appear as the nature of the invention is better understood, the same consists in the novel combination and arrangement of parts hereinafter fully described, illustrated in the accompanying drawings and then claimed.

In the drawings forming a part of this application and in which like designating characters refer to corresponding parts throughout the several views: Figure 1 is a perspective view of one form of the device. Fig. 2 is a perspective view of the preferred construction being slightly larger than that illustrated in Fig. 1 and provided with a retaining bail and lid retainers. Fig. 3 is a central longitudinal sectional view of the device. Fig. 4 is a transverse sectional view thereof. Fig. 5 is an end view of the frame-work in its closed position. Fig. 6 is a perspective view of an end portion of the frame-work unfolded. Fig. 7 is a perspective view of an edge portion of the device showing a hinge member for the lid, and Fig. 8 is a transverse sectional view of one of the lid hinges.

In describing the drawings, like designating numerals will be employed in connection with all of the views including Figs. 1 and 2, as Fig. 2 includes all of the elements disclosed in Fig. 1. The device broadly consists of a metallic frame-work 10 over which a flexible covering 11, formed of such material as leather or canvas is positioned and is preferably secured by being lapped over the two part wire rim 12 forming the entrance opening of the device and as best illustrated at 13 in Figs. 4 and 7 of the drawings.

A central bottom bow 14 is hinged to similarly shaped side bows 15 at their free ends by means of pivoting rivets 16, while spacing struts 17 are hinged together as at 18 and are pivoted at their opposite free ends to the end portions 19 of the bows 15 as at 20. The bows are positioned within the flexible covering 11 and the inner ends of the rim members 12 are pivotally mounted upon the rivets 16, while hooks 21 are carried by the rim members 12 and are adapted to engage within eyes 22 of the bail ends 19 for retaining the rim members in substantially rectangular form when the bows 15 are outspread in their operative positions and with the struts 17 pressed in substantial alinement with each other and with the stop lug 23 of one of the said struts engaging the upper edge of the companion strut.

It will be noted that the bottom portions of the bows 15 are curved in cross section which prevents the same from piercing the flexible covering and also assists in allowing the separation of the said bows to stretch the covering in its bag formation and in contact with the centrally positioned bottom brace 14 as best illustrated in Fig. 4.

Two equal sized lid members 24 are hinged to the opposite rim members 12 by means of short links 25, while securing straps and buckles 26 and 27 respectively may be employed for retaining the said lids in their closed positions in a single plane in flat engagement above the rectangularly arranged rim members 12 when the device is assembled.

A handle or bail 28 is arranged transversely of the bag and removably secured to opposite hooks 29 secured at opposite points to the rim members 12, while a second shorter handle 30 is positioned longitudinally of the bag if desired, as shown in Fig. 2 being se-

cured to one of the lid members 24. When desired to fold or collapse the device, the lids 24 are opened and the hooks 21 released and the struts 18 folded together by drawing the same outwardly and whereupon the side bows 15 may be brought substantially together inclosing the central bow 14 therebetween while the rim members 12 as well as the lids 24 will fold flatly as best illustrated in Fig. 5, the flexible covering 11 readily being folded with the frame-work as the only attachment thereof with the frame-work is in connection with the rim members 12 as hereinbefore specified. It will be seen that to set up the device, a substantial reversal of the above operation accomplishes the results and that the device will then assume its bag formation with its outwardly bowing opposite ends and the substantially rectangular rim 12 will be of less area than the central longitudinal sectional area thereof at a point between the lids and the bag bottom.

While the form of the invention herein shown and described is what is believed to be the preferred embodiment thereof, it is nevertheless to be understood that minor changes may be made in the form, proportion and details of construction without departing from the spirit and scope of the invention as claimed.

What I claim as new is:—

1. A collapsible bag frame comprising a bottom bow having upturned end portions, side bows having upturned end portions hinged at their free ends to the free ends of the said bottom bow end portions and having their bottom portions curved in cross section, spacing struts pivoted to each other and to

the end portions of the said side bows, rim sections pivoted together at the pivotal connection between the said bows and being substantially rectangular in form when the device is in its assembled position, eyes carried by the end portions of the said side bows and retaining hooks carried by the rim members and engaging the said eyes.

2. A collapsible bag frame comprising a bottom bow having upturned end portions, side bows having upturned end portions hinged at their free ends to the free ends of the said bottom bow end portions and having their bottom portions curved in cross section, spacing struts pivoted to each other and to the end portions of the said side bows, rim sections pivoted together at the pivotal connection between the end portions of said bows and being substantially rectangular in form when the device is in its assembled position, eyes carried by the end portions of the said side bows, retaining hooks carried by the rim members and engaging the said eyes, equal sized lids flatly arranged upon the said rim members, hinging links connecting the said lids and the said rim members, closure retaining means connecting the said lids, a removable bail positioned transversely of the lids and secured at opposite points to the said rim members, and an auxiliary handle secured longitudinally to one of the said lids.

In testimony whereof I affix my signature in presence of two witnesses.

MICHAEL DESPOT.
